UNITED STATES PATENT OFFICE.

GEORGE BERNERT AND JACOB BERNERT, OF MILWAUKEE, WISCONSIN, ASSIGNEES
TO BERNERT MANUFACTURING COMPANY, OF MILWAUKEE, WISCONSIN, A COR-
PORATION OF SOUTH DAKOTA.

FEED-DRUM FOR PNEUMATIC ELEVATORS.

1,346,293.

Specification of Letters Patent. Patented July 13, 1920.

Application filed December 5, 1914. Serial No. 875,556.

To all whom it may concern:

Be it known that we, GEORGE BERNERT and JACOB BERNERT, both citizens of the United States, and residents of Milwaukee, in the 5 county of Milwaukee and State of Wisconsin, have invented certain new and useful Improvements in Feed-Drums for Pneumatic Elevators; and we do hereby declare that the following is a full, clear, and exact 10 description thereof.

Our invention has for its primary object to provide a simple, economical and effective means for positively introducing granular or disintegrated substances into the valve- 15 controlled trunk of a pneumatic elevator mechanism, the said substances embodying grains or like material. The pneumatic elevator mechanism utilized in conjunction with our present invention is similar to that 20 disclosed in our U. S. Patents No. 1033865, July 30, 1912, No. 977849 and No. 1002556.

The specific object of our present invention is to provide a vertically positioned feed drum for such elevators wherein friction is 25 reduced to a minimum and the grain or other product being operated upon is thus discharged into the trunk with but one change of general direction. Hence the amount of power required for the feed is reduced to a minimum and at the same time a uniform and constant feed is insured to relieve the pneumatic force employed from variations in duty with the result that said 30 force can be economically employed to deliver grain at greater distances.

Another object of our invention is to simplify the details of construction of the feed drum, whereby an efficient and durable device is produced at a low cost in manufac- 40 ture.

With the above objects in view the invention consists in certain peculiarities of construction and combination of parts as set forth hereinafter with reference to the accompanying drawings and subsequently 45 claimed.

In the drawings—

Figure 1 represents a sectional elevation of a feed mechanism embodying the features of our invention, the section being indicated by lines 1—1 of Figs. 2 and 3;

Fig. 2, a detailed side elevation of the upper portion of a feed mechanism showing the gear connections, and

Fig. 3, a detailed cross-section of the 55 drum, the section being indicated by line 3—3 of Fig. 1.

Referring by characters to the drawings, 1 represents a pneumatic elevator trunk leading from a fan casing 2, whereby the air 60 pressure is generated and discharged into the trunk, which trunk is provided with a grain receiving aperture 3. The aperture 3 has fitted thereover a valve-box 4 flanged at its upper edge for the reception of a cor- 65 responding flange 5' of a vertically disposed boot 5 which is rectangular in cross-section to correspond to the rectangular mouth of the valve-box 4, the front wall 4' of said valve-box being flared forwardly in the di- 70 rection of travel of grain through the trunk. The boot is integrally cast with a vertically disposed drum 6', the circular bore of which intersects the rectangular bore of the boot.

The rear wall of the boot 5 is provided 75 with an obliquely disposed integral gland 7 which constitutes a guide for a valve-con- 80 trolled stem 8 that projects therethrough. The inner end of said valve stem is in hinged connection with a horizontally positioned flap valve 9, which flap valve is hinged at its rear edge to a rectangular one-piece skele- 85 ton valve-plate 10, the said plate being fitted between the valve-box flange and boot flange and confined therebetween by retaining bolts 11, which serve to clamp the three ele- 90 ments together.

The outer end of the valve stem 8 is pro- 95 vided with a washer and nut 8', between which members and the end of the boot 90 gland a coiled spring 7' is interposed to yieldingly support the flap valve in its closed position whereby the trunk is normally cut off from the feed cylinder 6'.

The feed cylinder 6' is flanged at its up- 95 per end and closed by a head 12 having a central hub projecting therefrom for the re- ception of one end of a shaft 13, the oppo- 100 site lower end of which shaft is stepped into a boss 14' that forms part of an arm 14, 100 which arm is blade-like in cross-section whereby it offers the least resistance to grain traveling through the cylinder to the boot portion thereof, it being understood that the said arm is secured to the upper 105 portion of the rear wall of the boot by suit- able webs. The shaft 13 carries a spiral conveyer blade 15, which extends from the

arm 14 to a point spaced slightly above the lower edge of a cylindrical obliquely inclined feed nozzle 16, the inclination of which feed nozzle is forwardly and upon the same general plane as the front wall 4' of the valve box. Hence it is apparent that the angle at which the material enters the drum is tangential to its line of travel through said drum, whereby friction is 10 eliminated to a maximum. It will also be seen that the upper end of the drum is clear of obstructions between the last flight of the spiral blade and the drum head to thus form a grain receiving cavity whereby grain entering the nozzle 16 is not liable to back up or choke in its downward feed movement.

The end of the shaft 13 projects beyond the head and carries a beveled gear-wheel 17 for meshed engagement with a beveled 20 gear-wheel 17' which is fast upon a transversely disposed countershaft 18, the same being journaled in boxes which form terminals of arms 19 that constitute part of the drum head. The front wall of the boot 25 5 has secured thereto ears 20' of a barrel 20, which barrel incases and forms a journal box for a drive-shaft 21, the same being provided with a pulley 21' at one end for belt gear connection to the fan-shaft 2'. A 30 sprocket-wheel 21" is fast to the opposite end of the drive-shaft for belt gear connection to a larger sprocket-wheel 22, which is fast upon the counter-shaft 18.

From the foregoing description it is obvious that the grain or other product to be conveyed can be elevated from a lower plane to the mouth of the drum nozzle 16 by any suitable elevator mechanism, not shown, which elevator mechanism in practice is 40 preferably of the bucket type. After the grain has been deposited in the nozzle 16 in desired quantities, it is manifest that the spiral blade 15 will sustain the gravity load and gradually permit said grain to be fed in a uniform stream to the boot therebelow and when the boot is entirely filled, the action of the spiral blade exerting force thereon will cause the valve 9 to open in opposition to a spring pressure whereby a uniform 45 quantity will be continuously forced into the air trunk 1, the valve 9 preventing any back leakage of air therefrom which would other-

wise impair the pneumatic feed through the air trunk. Thus in the feed of the material all possible friction is eliminated and a uniform flow is delivered to the pneumatic appliance at all times, which uniformity is materially affected due to the fact that the drum is vertically disposed and constructed as previously stated.

We claim:

1. In a pneumatic conveying apparatus, the combination of a conveying air duct, means for procuring a pressure current of air through said duct, an elongated feed conveyer casing having one end in communication with the air duct above the path of the air current therein, a valve pivotally mounted within the feed conveyer casing adjacent its point of communication with the air duct, and a conveyer extending longitudinally in the feeder casing and engaging work material therein to feed said work material toward the valve, said valve extending transversely across the casing and being intersected by the major axis of the casing in closed position of said valve whereby to receive direct thrust pressure of the work material in the casing by pressure exerted by said feeding means.

2. In a pneumatic conveying apparatus, the combination of a conveying air duct, means for procuring a pressure current of air through said duct, an elongated feed conveyer casing having one end in communication with the air duct above the path of the air current therein, a valve pivotally mounted within the feed conveyer casing adjacent its point of communication with the air duct, said valve extending transversely across the casing, and a spiral conveyer in the feeder casing having its axis intersecting the plane of the valve when closed.

In testimony that we claim the foregoing we have hereunto set our hands at Milwaukee, in the county of Milwaukee and State of Wisconsin in the presence of two witnesses.

GEORGE BERNERT.
JACOB BERNERT.
